UNITED STATES PATENT OFFICE.

CHARLES A. SIGMOND, OF FREEPORT, NEW YORK.

ICE-CREAM-CAN TONGS.

1,351,493.

Specification of Letters Patent. Patented Aug. 31, 1920.

Application filed August 29, 1919. Serial No. 320,639.

To all whom it may concern:

Be it known that I, CHARLES A. SIGMOND, a citizen of the United States, residing at Freeport, in the county of Nassau and State of New York, have invented a new and useful Ice-Cream-Can Tongs, of which the following is a specification.

This invention has reference to lifting tongs, and more particularly to tongs employed in lifting ice cream cans from the freezers, in which the same are supported.

The primary object of the invention is to provide tongs of this character having clamping jaws, adapted to clamp the upper portion of an ice cream containing can, to facilitate the easy removal of the same.

A further object of the invention is to provide adjustable means for clamping the can, to enable the tongs to be employed for use, with cans of various dimensions and sizes.

A still further object of the invention is to provide means for locking the jaws in their adjusted positions, thereby preventing the same from releasing their hold, on the can under operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring to the drawing:—

Figure 1 illustrates a side elevational view of tongs, constructed in accordance with the present invention, as applied to an ice cream can.

Fig. 2 illustrates a bottom plan view of the same.

Having reference to the drawing in detail, the reference character 5 indicates the body of the tongs, which is provided with the internal screw threads 6, to receive the threaded shank 7 of the operating bar 7'.

The upper end of the operating bar 7', is provided with a transverse opening 8, which accommodates the hand lever 9, which as shown is substantially long and provided with the heads 10, formed on the respective ends thereof, which heads prevent displacement of the handle 9, from the opening 8, when the same is in operation.

The lower end of the operating bar 7', is provided with a head 11, which is provided with a circular groove 12, the same being for the purpose of accommodating the inner ends 13, of the clamping jaws 14, thereby permitting the head to revolve with relation to the jaws 14.

These clamping jaws 14, include substantially right angle members, the inner ends thereof being provided with the heads 15, which as before stated are associated with the head 11, of the operating bar 7', whereby movement of the operating bar produces a relative movement of the clamping jaws, 70 for forcing the outer, or depending portions thereof, into engagement with the ice cream can, under operation, the extreme lower ends of said depending portions of the jaws 14, being provided with the lugs 16, forming 75 shoulders 17, for engaging under the bead 18, of the ice cream can 19, shown more particularly by Fig. 1 of the drawing.

Radiating from the body 5, of the tongs, are the right angled arms 20, each of which being provided with a depending forked portion 21, which forked portion is adapted to receive and accommodate one of the clamping jaws 14, a bolt 22, passing through suitable registering openings, in the forked 85 ends of the arms 20, provides means for pivotally connecting the clamping jaw to the arm 20.

From the foregoing it will be seen that if it becomes necessary to remove an ice cream can from its freezer, it is only necessary to move the operating bar 7', to expand the jaws, to the limit of their outward movements, whereupon the lower ends 16 thereof, are forced into the ice which usually surrounds the ice cream can. The operating bar 7' is now operated to contract the jaws, to a position to engage the bead 18 of the can, whereupon the jaws are securely locked to the can and the device is now in a position to remove the can, the same being accomplished by a slight upward movement, or pull directed to the body of the tongs by a person pulling on the bar 9.

Having thus described the invention, 105 what is claimed is:—

1. Tongs including a body portion, right angled arms extending from the body portion, each of said arms having a depending portion, clamping jaws including right angled members, means for pivotally connecting the clamping jaws to the right an-

- gled arms, means on one end of each of the clamping jaws for coöperating with an ice cream can, an operating bar threaded to move through the body, a head on one end 5 of the operating bar, means for connecting the head and one end of each of the clamping jaws whereby movement of the operating bar produces a relative movement of the clamping jaw.
- 10 2. Tongs including a body portion having a central threaded opening, arms formed integral with the body portion, clamping jaws pivotally connected to the arms, a threaded operating bar operating in the threaded opening in the body, means for providing a connection between the clamping jaws and operating bar whereby movement of the operating bar produces a relative movement of the clamping jaws.
- 15

3. Tongs including a body portion, a 20 threaded operating bar adjustably supported within the body portion, a head formed on one end of the operating bar, said head having a groove, clamping jaws associated with the body, each of said jaws having an 25 arm provided with a head on the extreme end thereof, said heads of the clamping jaws being positioned in the groove, whereby movement of the operating bar produces a relative movement of the clamping jaws. 30

In testimony that I claim the foregoing as my own, I have hereto affixed my signature in the presence of two witnesses.

CHARLES A. SIGMOND.
